UNITED STATES PATENT OFFICE.

HOWARD F. SNYDER, OF NEWTON, IOWA, ASSIGNOR TO THE MAYTAG COMPANY, OF NEWTON, IOWA, A CORPORATION OF IOWA.

WRINGER.

1,316,601.

Specification of Letters Patent. Patented Sept. 23, 1919.

Application filed May 15, 1915. Serial No. 28,272.

To all whom it may concern:

Be it known that I, HOWARD F. SNYDER, a citizen of the United States, residing at Newton, in the county of Jasper and State 5 of Iowa, have invented certain new and useful Improvements in Wringers, of which the following is the specification.

Wringers as heretofore made, in so far as I am aware, are always provided with considerable mechanism, such as tension springs, adjusting screws, pressure bars, etc., mounted in the top of the wringer frame and projecting upwardly a considerable distance above the rolls. This is an unwieldly and 15 disadvantageous construction for the reason that such projections take up a great deal of room, require a large amount of storage space and increase shipping charges. Again, these upstanding projections are unsightly 20 and in the way and are very apt to catch and tear the clothes of the operator. While wringers of the prior art have some times been provided with wringer release devices of various forms it has heretofore been impossible to instantaneously release the tension of the wringer rolls without displacing various springs, pressure plates, or other parts, which must be reassembled and put back in the frame before the wringer can 25 again be put into operative condition.

Another disadvantage of the old form of construction is that whenever the wringer is released, (if mechanism for that purpose be provided) it has been necessary not only 30 to replace the various springs and other parts which have been displaced by the release of the wringer roll, but to each time reset the tension before the wringer can again be operated. Similarly if the tension 35 is relieved by letting up the springs, these springs must be tightened again and their tension reset prior to the operation of the wringer. Either of these operations consumes so much time and is so much trouble 40 that in actual use, wringers of the old form are generally neither released nor relieved of their tension before they are put aside after washing has been done, but are left in tension, which is bad for the rolls.

To overcome these various defects and disadvantages my present construction has been devised in which the wringer is of compact construction having no upwardly projecting parts; in which the wringer can be instantly 45 released without disassembling the tension

elements; in which the two rolls when released may be widely separated to lay them both open to view; and in which after its release the wringer may be instantly put in operative condition without resetting or re-adjusting the tension means. 60

It is another object of my invention, to provide a wringer of simple, economical and compact construction having no parts which project high above its support to take up 65 excessive room, or to catch and tear the clothes of the operator.

It is another object of my invention to provide a wringer in which the upper roll may be swung away and widely separated 70 from the lower roll to lay both rolls open for inspection, cleaning or removal of any material which may become wound in them in the operation of the machine, or for other purposes. 75

It is another object of my invention to provide a wringer comprising two hinged arms and releasable tension means acting from below the lower arm but projecting therethrough so as to engage the upper arm 80 and draw it downwardly toward the lower arm, whereby the tension elements of the wringer are situated and controlled from below and the upper may be swung clear 85 without disturbing them.

It is another object of my invention to provide a means whereby the tension elements when released are held in a position in which they may instantaneously reengage 90 the wringer so as to again put it in operative condition.

Other objects and advantages of the invention will appear as the description to follow proceeds.

In the drawings: 95

Figure 1 is a front elevation partly in section of my new wringer.

Fig. 2 is a plan view partly in section of the same.

Fig. 3 is an end elevation partly in section. 100

Fig. 4 is a sectional view, the section being taken perpendicular to the wringer rolls.

Fig. 5 is a perspective view of the wringer closed, or in operating position, without the drain board. 105

Fig. 6 is a perspective view of the wringer in open or released position, without the drain board.

In the drawings: 1 represents a casting or bracket formed integral with the lower cas- 110

ing of the wringer hereinafter described, and affording means for the attachment of the wringer to a support, the particular depending bracket 1 being only one of several ways by which the wringer may be mounted, and in this instance being designed to be secured to a swinging support so that the wringer may be swung from one position to another. Preferably integral with 10 the bracket 1 is the lower housing structure comprising enlarged housings 2 for the lower wringer roll gears, the intermediate shell portion 3 inclosing the lower wringer roll and the housings 4 to hold the bearings of 15 the lower roll shaft. The housings 4 are substantially semicircular in form and are provided with reduced outwardly extending flanges 5 to protect the roll shaft. Recesses 6 are provided in the housings 4 through 20 which project the corners 7 of the ball races 8 for the shaft of the lower wringer roll. These ball races 8 are pushed into the housings 4 from above and when in position are held by the notches 6 and by the stiff resilient 25 slightly inturned fingers 9 at the forward upper corners of the housings 4. The housings 4 are integrally connected with the housings 2 by the reduced webs 10. The housings 2 are provided, as stated, to accommodate 30 the lower gears 11 upon the lower wringer roll shaft 12, upon which is mounted the lower wringer roll L. The shaft 12 is extended and key-slotted at one end to receive a handle or a driving gear as clearly 35 shown in Figs. 1, 5 and 6. These housings 2 are provided with front and rear extensions 13 and 14 having flanges projecting toward the roll shaft, as shown at 15-16-17 and 18, flanges 15 and 16 being separated by slots 40 19 for the reception of the upper and lower roll shafts, which slots extend downwardly to the reduced web 10, as shown in Fig. 1. Flanges 17 and 18 are cut-out, as shown at 21 and 22 for a purpose hereinafter to be described, and are provided with guard and 45 strengthening ribs 18' and are provided with slots 20 to accommodate the lower wringer roll shaft 12. The front extensions 13 are enlarged, as shown at 23, and project vertically upwardly. The rear housings 14 are flared backwardly, as clearly shown in the drawings, this construction being adopted to permit the upper half of the casing to swing into and out of telescoping relation with the 50 lower half of the casing, as hereinafter more fully described. The shell 3 which connects the housings 2 and incloses the lower roll L terminates at its upper sides in the integrally formed lips 24 which are integral with the 55 extensions 25 on the inner flanges 17, and project longitudinally, as indicated at 26 to overlap these extensions, and are provided with end closures 26', all corners being rounded so as to provide a smooth entrance or 60 mouth in which the material to be operated

upon cannot catch. Projecting downwardly from the housing 3 are lugs or ears 27 which are slotted, as shown at 27', and provided with apertures, as shown at 28, for the reception of cotter pins to provide a bearing 70 support for the pivots of a reversible drain board 29 which may be used to run the water off in either direction.

Integrally formed with and projecting rearwardly at each end from the housing 75 structure 2-10-4-5 just described, are arms 30 provided adjacent the wringer with circular enlargements 31 and at their rear ends with a pair of lugs 32 having flat rear sides 33. Hinged in the lugs 32 by means 80 of bolts 34, or by equivalent means, are upper arms 35 having downwardly projecting webs 36 situated between the lugs 32 and perforated to receive the bolts 34. The rear ends of the arms 35 are provided with flat overhangs 37, the construction being such that when the upper arms are swung to open position, as indicated in Fig. 6, the flat overhangs 37 will rest against the flat rear sides 33 of the ears 32 to hold the 90 wringer in open position. The arms 35 at their forward ends are formed integrally with a housing construction somewhat the same as the lower housing hereinbefore described, incasing the upper wringer roll U 95 and adapted to telescope into the lower housing to completely inclose both rolls. This housing construction comprises end housings 40 provided with reduced extending flanges 41 and having recesses to receive 100 the projecting corners 42 of the upper ball races 43, and stiff resilient extensions 44 to lock the ball races 43 in position. The upper ball races 43 carry the shaft 12' of the upper roll U which is provided at either 105 end with gears 11' meshing with the gears 11 of the lower roll shaft, to cause both rolls to rotate in unison during the operation of the wringer. Projecting inwardly from the housings 40 are reduced flanges 110 45 integral with the top housing structures 46 for the upper wringer roll gears. The top housing structure 46 is provided with integral depending flanges 47 which are adapted to fit into the lower housing above 115 described. The top housings 46 close the tops of the lower housings, as indicated in Fig. 5, flanges 45 coming down outside the flanges 15, as clearly shown in that figure. Integrally connecting the housings 46 is the 120 casing or shell 48 for the upper roll which terminates at either end in the flat webs 50 which form the inner sides of the top housings 46 and rest in the cut away portions 21-22 of the lower casing. Projecting 125 from the upper casing 48 are lips 52 having rounded edges for guiding the clothes to and from the wringer rolls.

The upper arms 35 are provided with enlargements 55 which are countersunk, as 130

shown at 56, and provided with stop lugs, as shown at 57. In the bottom of the countersinks 56 are slots 58. The enlargements 31 in the lower rolls are provided with countersinks 31' and openings 31² centered with the slots 58 just described. T-headed bolts 60 pass through the orifices 31² and tension is applied to these bolts by compression springs 63, the upper ends of which 10 rest in the countersink 31' and the lower ends against the washers 64, adjustable by means of thumb screws 65. Collars 61 are provided upon the bolts 60 and rest upon the tops of the arms 30 to limit the downward movement of the bolts under the influence of springs 63, the space between the collars 61 and the heads 66 of the bolts 60 being sufficient to accommodate the bottom of the countersinks 56, as clearly seen in 15 Fig. 3. The right hand collar 61 is cast integral with a bell crank 67 and handle 67' connected by a link 68 which is bent downwardly and then inwardly, as indicated at 69—70, so that its medial portion 71 fits 20 under the lip 24 of the lower casing and is thus out of the way, the opposite end of the link being formed in the same way, connecting with a crank 72 rigid with the collar 61 upon the opposite T-headed bolt. By 25 30 this means both bolts are turned simultaneously.

When the handle 67' is in its outward position, as shown in Fig. 5, both T-headed bolts 60 are turned so that their heads are 35 across slots 58, and rest against the stops 57 if closed, and the wringer is thus locked in operative position with the wringer rolls in contact. The introduction of clothes between the wringer rolls will tend to separate 40 these rolls against the full tension of springs 63. If any mishap or obstruction occurs in the operation of the wringer (such as the catching of the fingers of the operator between the rolls, or the winding of the 45 clothes thereon), the handle 67' has simply to be pulled to approximately the position shown in Fig. 6 whereupon the T-heads 66 of the bolts 60 will register with the slots 58 releasing the entire upper half of the 50 wringer, which may then be swung to the position shown in Fig. 6 instantaneously releasing the upper roll and laying open both wringer rolls for inspection, cleaning, or for other purposes. When it is desired to resume 55 operations, the upper half of the wringer is lowered, the casings telescoping, as shown in Fig. 5 to completely inclose the entire machine except for the space between the upper and lower lips 24 and 52, through 60 which the clothes are fed into and from the bite of the rolls. The upper arms 35 then assume the position shown in Figs. 3 and 5 wherein the bottoms of the countersinks 56 rest upon the collars 61, and the bolts 65 may be turned by means of handle 67' to

lock the wringer again in operative position. It is particularly to be noted that there is no displacement of any springs or other mechanisms when the wringer is released. This feature I consider broadly new. It is also to be noted that no adjustment whatever is necessary of the springs 63 when the wringer is released or put back in operative condition, their tension having once been adjusted remains so adjusted indefinitely. I consider this feature highly important and also broadly new. The wringer when assembled is completely inclosed and incased so that there is no possibility of catching or tearing any clothes. 70 Moreover, when the wringer is closed the only conspicuous projection thereon is the handle 67'. This is an important feature, for the operator if her fingers are caught in the rolls has only to grab the only projection in sight to be released. Where there are several projections on the machine the operator whose fingers are caught is likely in her confusion to grasp the wrong one first and thus to be severely injured before 75 she releases herself. This feature I also consider broadly new. The tension means project downwardly instead of upwardly, as is usually the case, forming a compact construction which takes up very little room. 80 When released the entire wringer may be opened up, as shown in Fig. 6, so that every part thereof is accessible. 85

Having described my invention, I claim:

1. A wringer comprising two pairs of 100 arms hinged together, a wringer roll in each pair of arms, resilient means for forcing said pairs of arms together and a single means for instantaneously and completely releasing one pair of said arms, whereby the 105 same may be swung back on its hinge completely free from the other pair of arms and the releasing means.

2. A wringer comprising a bracket adapted to be applied to a support, an arm on 110 said bracket, another arm hinged on said first arm, a bolt having a non-circular shaped head at one end and passing through apertures in said arms, the aperture in the hinged arm adjacent the bolt 115 head being adapted to permit the latter to pass therethrough when in one position, a spring surrounding said bolt and adapted to force said arms one toward the other, and means for turning said bolt to bring its 120 head to register with the adjacent aperture whereby the adjacent arm is released to permit it to be swung entirely free from said bolt.

3. In a wringer, a stationary support having a roll therein, a movable support having another roll therein, tension means including a resilient member for drawing said movable support toward said stationary support, said resilient member being located on 125 130

- the side of said movable support toward the stationary support and means for instantly releasing said movable support from said resilient member.
5. In a wringer, an arm adapted to be fixedly mounted and carrying a wringer roll, an arm movably mounted and carrying another wringer roll, tension means for drawing said arms together and including 10 a spring member, said spring member being located on the side of the stationary arm remote from the movable arm, and a wringer release, whereby said movable arm may be released and moved away from said stationary arm without displacing said spring member.
5. In a wringer, an arm carrying a roll adapted to be fixedly mounted, another arm carrying a roll hinged thereto and adapted 20 to be swung back thereupon so as to widely separate said rolls, tension means located below said stationary arm but having a part projecting thereabove to engage said movable arm and resist separation of said rolls, 25 and means for instantaneously releasing said tension means.
6. In a wringer, a roll support, another roll support movable with relation thereto, a bolt mounted in the first roll support and 30 adapted to engage the second roll support, tension means for acting on said bolt to create pressure between the rolls, a release means for releasing said bolt from the movable roll support and means to prevent the 35 displacement of said bolt when released.
7. In a wringer, a roll support, a second roll support movable relatively to the first support, tension means for resisting movement of said movable support away from 40 the other support so as to exert pressure between the rolls in operation, including means to disengage said means from said movable support to permit the latter to be moved away from the first support, and means to retain said tension means when disengaged from said movable support in position for reengagement therewith without changing the tension thereof.
8. In a wringer, in combination, a pair of rolls, tension means to resist separation of 50 said rolls, means to operatively engage or disengage said tension means from one of said rolls without changing the tension of said tension means.
9. In a wringer, a lower pair of arms, an 55 upper pair of arms, bolts passing through apertures in said arms, springs coöperating with and forcing said upper and lower arms together and means for instantaneously, simultaneously and completely releasing the 60 bolts from one pair of arms without longitudinal movement of said bolts.
10. In a wringer a pair of arms, each carrying a roll one above the other, a bolt passing through apertures in said arms, a 65 spring tension element for forcing said pair of arms together and mounted on said bolt to extend down behind the lower roll to be out of the way as an interfering obstruction, and an instantaneous release handle on said 70 bolt adapted to instantly release the upper roll from the lower when operated, said handle projecting out at one side from said arms and constituting the most prominent projection at this portion of the wringer 75 whereby it can be quickly and accurately grasped when instantaneous release of the upper roll is desired.
- In witness whereof, I hereunto subscribe my name to this specification in the presence 80 of two witnesses.
